HEATING CONTROL SYSTEM

William J. McGoldrick and Frederick S. Denison,
 Minneapolis, Minn., assignors to Minneapolis-
 Honeywell Regulator Company, Minneapolis,
 Minn., a corporation of Delaware

Application July 15, 1938, Serial No. 219,368

14 Claims. (Cl. 158—117.1)

Our invention pertains to the art of heating control devices and is particularly concerned with a temperature controlled gas valve or the like having novel safety features and characteristics.

Referring generally to our invention, we employ a temperature responsive safety device for closing a gas valve or the like which closes the valve whenever an unsafe condition is indicated by the device. In the event of shut-down brought about by an unsafe condition, the device must be manually reset to its original position. Our device is of such a nature that while it is being reset, that is manipulated to its original position, the parts coact in a manner to maintain the valve closed. Thus the valve cannot under any circumstances be opened until the device automatically remains in its original or reset position indicating the disappearance of the unsafe condition.

The invention adapts itself preferably to a gas fired heating system wherein the safety shutdown device is normally energized by a thermocouple heated by a gas pilot flame. Upon extinguishment of the flame, which, of course, is a dangerous condition, the device is deenergized and closes the valve. The device may then be manually reset to its energized position, the resetting mechanism being of such a nature as to keep the valve closed during manipulation thereof and the device will, of course, not remain in its energized position until the pilot flame is again burning. Elimination of a serious hazard is therefore avoided in that the gas valve cannot be even momentarily opened to admit passage of shots of combustible fluid therethrough while an operative manipulates the safety shut-down device in an effort to reset the same after a shutdown due to pilot flame failure. Thus after a safety shut-down any opening of the valve is dependent upon successful remedying of the unsafe condition which brought about the shutdown. In other words, in the instance of a pilot flame responsive device as we have referred to, for example, if the pilot flame goes out shortly after an operative has relit it, our invention precludes the danger of his momentarily opening the valve and admitting a shot of gas to the burner while he attempts to manually reset the safety device. The grave danger otherwise present is obvious; the operative upon finding he cannot manually reset the device, again lights the pilot burner, and without our invention, having admitted a shot of gas to the main burner, a serious explosion results.

The principal object of our invention is to

provide a device for eliminating the danger, the nature of which we have outlined above.

Another object of our invention is the provision of a thermo-couple energized device for closing a fluid fuel gas control valve or the like upon the occurrence of an unsafe condition such as extinguishment of a pilot flame.

Another object is the provision of an automatic valve closing device having manual reset apparatus which acts to keep the valve closed when the device is being reset.

Another object is the provision in a pilot controlled gas valve of an automatic safety shutdown device which closes the main valve and at the same time closes an auxiliary valve preventing any further flow of gas to the combustion region.

Another object is the provision of an automatic temperature responsive valve closing device having manual reset apparatus which acts to keep the valve closed when the device is being reset and additional temperature responsive mechanism for automatically operating the manual reset apparatus in a manner to close the valve at unsafe temperatures.

Other useful objects and advantages of our device will become apparent as the specification proceeds, the invention residing in the structure, combination, and arrangement of parts and toward which we have directed the appended claims.

Figure 1 of the drawings is a cross-sectional view of a preferred form of the valve of our invention taken along the line 1—1 of Figure 2, and showing diagrammatically the manner of incorporation of the valve in a gas fired heating system including the controls therefor.

Figure 2 is a plan view of the valve of Figure 1.

Figure 3 is a view partly broken away to show in cross-section a modified form of our improved valve.

Referring to Figure 1 of the drawings, numeral 1 indicates generally the body of our valve. In our particular arrangement, we have incorporated a pressure regulating valve within the same structure as the control valve, the pressure regulating valve being shown at the lower part of the valve structure of Figure 1. The valve apparatus has an inlet at 2 which may be connected by suitable means to a gas supply main, it being understood that we preferably employ our invention in a gas fired heating system. The gas which may be admitted through inlet 2 passes through the pressure regulator and then through the control valve, as we will later describe, and passes out

through an outlet indicated at 3. The outlet 3 may be connected by a conduit 4 with a gas burner 5 of conventional type disposed within a unit air heater indicated generally at 6. While other types of heating apparatus may be employed with our invention, we have chosen to disclose it in connection with the heater 6 which may be one of conventional type comprising a casing, as shown, having disposed therewithin a plurality of cells 7 through which air may be forced in heat exchange relation with the gases of combustion within the heater. The cells 7 may be connected with a suitable inlet header, or the like, 8 and a device such as a fan or otherwise may be employed to force the air of the room or other space being heated through the heater 6. The heater 6 has a stack or flue 9 through which the burnt gases of combustion may be carried away. Numeral 10 indicates a tube which may communicate with the inlet side of the valve apparatus and which conveys gas to a constantly burning pilot burner 11, as conventionally used in this type of apparatus.

Referring again to the valve structure, it will be seen that the internal configuration is such as to form an inlet chamber 12 from which gas may pass through the pressure regulating valve and thence to the control valve. The seat of the pressure regulating valve is formed by a screw plug 13 which engages in screw-threaded relation with a corresponding opening in the lower wall portion of the inlet chamber 12. The lower part of the valve body 1 has an annularly shaped boss 14, the surface of which corresponds in shape to the surface of a flange 15 formed integrally with a member 16 forming a part of the pressure regulating valve. The flange 15 is secured to the boss 14 by screws, or the like, which do not appear on Figure 1, there being interposed between the flange 15 and boss 14 the peripheral portions of a circular diaphragm 17 which may be made of any suitable material, such as leather. Numeral 18 indicates the valve member of the pressure regulator, this valve member being secured by suitable means to a valve stem 19 having a screw-threaded portion 20 extending through the diaphragm 17. Disposed above the diaphragm 17 and adjacent thereto is a metal disc backing member 21 and on the lower side of the diaphragm is a spring retaining nut 22 which serves to retain the diaphragm, the valve stem 19, and the disc backing member 21 in their proper respective relation. The member 16 is substantially cylindrical in shape, as shown, and engaging therewith in screw-threaded relation is an adjusting screw 23 which carries a second spring retaining element 24 at its end within the member 16. Disposed between the spring retaining nut 22 and the spring retaining element 24 is a coiled compression spring 25 which engages with a suitable shoulder on each of the spring retaining members. Engaged on the adjusting screw 23 external of the member 16 are lock nuts 26 and 27 for rigidly securing the adjustment screw 23 in any desired position. Obviously, the tension of the coil spring 25 may be adjusted by adjusting the tension screw 23. The portion of the adjusting screw 23 external of the member 16 is protected by a cylindrically shaped guard 28 which frictionally engages the member 16.

The pressure regulating valve which has just been described operates in the conventional manner of such valves to maintain a constant pressure on its outlet side regardless of fluctua-

tions in pressure in the gas main which communicates with the inlet conduit and the details of this valve form no part of our invention.

Gas from the outlet side of the pressure regulating valve enters the chamber above the diaphragm 17 and then passes through a channel 30 formed in the casting comprising the body 1 of the valve to a chamber 31 in the inlet side of the control valve which we will next describe. The control valve indicated generally at 32 is also of the diaphragm type and has a seat at 33. The shape of the upper surface of the body 1 of the valve is partly circular and has also a rectilinear flat portion at 34 as may be more readily appreciated from an inspection of the plan view of Figure 2. The top or cover for the control valve comprises a housing 35 having a flange 36 similar to the corresponding portion forming the upper part of the body 1 and having a flat plate-like portion 37, the shape of which conforms to the portion 34 of the valve body. The flange 36 and the plate-like portion 37 of cover 35 are secured to the body 1 of the valve, the portions which are secured together having interposed therebetween the peripheral portions as shown of a diaphragm 38 which may be made of material similar to that of the diaphragm 17. Screws 43 (Figure 2) may be employed to secure the parts together in the same manner as previously described in connection with the pressure regulating valve. Disposed adjacent the central portion of the diaphragm 38 is a valve disc 39 made of suitable material which may be the same as the material of diaphragm 38 and on the opposite side of the diaphragm is a metal disc backing member 40. A metal disc backing member 41 may also be employed adjacent the valve disc 39, the discs and the diaphragm being secured together by a bolt 42, the bolt having washers disposed between its head and the metal disc backing member 40, as shown, if desired.

Within the housing 35 is disposed an electrical coil winding 45 having suitable insulation thereon, the ends of which extend through the fitting 46 in a side wall of the housing 35. External of the housing, the terminals of the winding 45 connect with a thermo-couple 47 disposed in the flame of the pilot burner 11 by electrical conductors 48 and 49. The coil winding 45 cooperates with an electromagnet 50 disposed there-within and for purposes which will presently become more apparent the coil winding 45 is of a type having very low resistance to flow of current therethrough and electromagnet 50 is made of iron having high permeability. The electromagnet is connected to a plunger 51, the lower end of which is pivoted to one end of a link 52 by means of a pin 53. The link 52 has a lug 54 on its lower side as shown. The plunger 51 extends through a spring retaining element 54 suitably secured within the housing 35, as shown. Secured to the lower end portion of the plunger 51 is a spring supporting disc 55 and between the disc 55 and the element 54 is disposed a coil spring 56 which encircles the plunger 51, as shown. The coil spring 56 continuously biases the plunger 51 downwardly. The opposite end of the link 52 is pivoted to the lower end of a second plunger 57 by means of a pin 58. The plunger 57 extends through a packing gland formed in the housing 35 comprising a packing nut 59 engaging in screw-threaded relation with the housing 35 and cooperating with packing material 60 so as to form a packing gland in the conventional manner. At the upper end of the plunger 57 is a

spring retaining nut 61 and between this nut and the packing nut 59 is a coil spring 62 which encircles the plunger 57 and engages with suitable shoulders on the nuts 61 and 59. The coil spring 62 biases the plunger 57 in an upward direction so that the right end of the link 52 is normally held in the position shown in the drawings.

The plunger 57 may be actuated by a mechanism which we have indicated generally at 65 on Figure 1. This mechanism is journaled on a spindle or shaft 66, this shaft or spindle forming an arbor mounted in a portion of the housing 35 as may be seen by referring to Figure 2. Inasmuch as the mechanism 65 is external of the housing 35 and as Figure 1 is a cross-sectional view, we have shown the mechanism 65 above the cross-sectional view of the valve structure itself in Figure 1. However, its exact position and that of the shaft 66 may be readily determined from Figure 2 and the operative relationship of the mechanism 65 with respect to the plunger 57 will be understood as the specification proceeds further. The mechanism 65 comprises a lever 67 having a U-shaped portion 68 engaged on the shaft 66. Encircling the shaft 66 is a coil spring 69 having one end 70 extending through the shaft 66 and having the other end 71 bent at right angles and engaging with an external surface of the housing 35, as may be seen on both Figures 1 and 2. The coil spring 69 biases the lever 67 in a clockwise direction for a purpose which will become apparent later. Also pivoted on the shaft 66 is a lever 74 having an angular portion 75 which is horizontally disposed and which may engage with the nut 61 as may be readily seen by referring to Figures 1 and 2. By means of a manual operating stem 76 which may have a suitable handle (not shown) the lever 74 may be rotated in a clockwise direction about the shaft 66 so that the angular portion 75 engages nut 61 so as to force the plunger 57 downwardly for a purpose which will be hereinafter described.

The U-shaped portion 68 of lever 67 has an integral angular configurated lug element 77 which is clearly shown on Figure 2 and which may engage with the horizontal angular portion 75 of the lever 74. Thus when the lever 67 is moved in a clockwise direction, the lug 77 may coact with the lever 74 and the nut 61 so as to force the plunger 57 downwardly in the same manner as described above. The lower end of the lever 67 is notched, as shown as 78, and engaged upon this end of the lever is a perforated member 79. The member 79 is attached to one end of a flexible transmission shaft 80 which extends through a curved tube 83 to the interior of the unit heater 6. The end of the flexible shaft within the unit heater 6 is attached to one end of a fusible link 81 which is responsive to the temperature within the heater adjacent the cells 7. The other end of the fusible link 81 may be supported in any suitable manner as, for example, by a bracket or the like indicated at 82. The end of the tube 83 terminates in a suitable fitting adjacent to and exterior of the unit heater 6. The end of the tube 83 which is adjacent to the control valve may be supported by means of a suitable bracket 84 and a second adjustable bracket 85, as more clearly shown in Figure 2. The bracket 85 is diagrammatically indicated on Figure 1 as part of the mechanism generally indicated at 65.

The valve 32 is preferably controlled by a three-way pilot valve forming part of a thermo-

statically controlled pilot valve unit indicated generally at 87. The three-way pilot valve comprises a body 88, the lower part of which is flanged as can be seen on Figure 2, the flanged portion being secured to the previously described portion 37 by screws 86 or the like as visible on Figure 2. Interposed between the flange at the lower part of the body 88 and the portion 37 is a gasket 89 for the purpose of providing a gas tight seal between the parts. The interior of the body 88 communicates by a port 90 with the inlet chamber 12 of the main valve structure, this port 90 extending through the gasket 89 through the portion 37, the diaphragm 38, and the body 1, as shown on Figure 1 of the drawings. The three-way pilot valve comprises a double valve member 91 cooperating with an upper seat formed in a plug member 92 which engages in screw-threaded relation with the interior portion of the valve body and which may also cooperate with a lower seat 93 formed within the body 88. The valve 91 is disposed within a chamber 94 which communicates by means of a port 95 with the interior of housing 35 above the diaphragm 38, the port 95 extending through the body 88 through the gasket 89 and through the portion 37, as shown best in Figure 1. Access may be had to the valve member 91 by means of a screw plug 96 in the side wall of the body 88, as shown. The chamber 94 communicates through the lower pilot valve with an outlet chamber 97 within the body 88 and the chamber 97 is connected through a suitable fitting to a tube 98 which communicates with an auxiliary pilot burner 99. The stem 100 of the pilot valve 91 extends through the plug 92 and is connected through a strain release mechanism to a device indicated at 101 forming a solenoid armature. The strain release mechanism comprises a coil spring 102 encircling the stem 100 and disposed so that one end engages the interior of the solenoid armature 101 and the other end abuts a nut 103 engaged on the end of stem 100. Obviously, the strain release mechanism provides a certain amount of resiliency in the connection between the solenoid and the valve member 91 for the conventional purpose for which strain release mechanisms are intended. In screw-threaded relation with the upper part of the body 88 is a ring nut 104 having a suitable annular shoulder which engages a cover member 105 and maintains it securely in abutting relation with the upper surface of the body 88. The cover member 105 has a flanged portion as shown secured to a guide 106 for the solenoid armature 101 and within which the solenoid armature is adapted to be reciprocated. The solenoid armature and the usual electric coil winding associated therewith are contained within a housing 107 which may be removed at will by loosening a thumb screw 108. The coil winding cooperating with the solenoid may be of conventional type and arrangement and its terminals extend through a suitable adaptor 109 in the side wall of the housing 107 and are connected with electrical conductors 110 and 111. The unit 87 may be controlled preferably by a room thermostat, for example, which may be of the conventional bimetallic element type as generally indicated at 112. The thermostat 112 includes a movable switch blade 113 cooperating with a fixed electrical contact 114, the contact 114 connecting with the wire 110 and the thermostat itself being connected to a wire 115. The wires 111 and 115 may connect to a source of external electrical supply at suitable voltage which

is not shown on the drawings. As will be well understood by those skilled in the art, when the thermostat closes indicating a need for heat the unit 87 becomes energized and the valve member 91 is moved so as to engage its upper seat so as to produce certain operation which will be more precisely set forth hereinafter.

Referring now to the operation of the modification of Figure 1, with the parts in the position shown, the thermostat 112 is satisfied and the valve member 91 is in engagement with its lower seat. With the pilot valve in this position, gas passes from the inlet chamber 12 through the port 90 to the interior of the pilot valve body 88, then through the plug 92 into the valve chamber 94 and then through the port 95 into the interior of the housing 35 above the diaphragm 38. Pressure above the diaphragm keeps the valve 32 closed as long as the thermostat 112 does not call for heat.

The pilot burner 11 burns continuously and consequently energizes the thermo-couple 47 so as to cause an energizing current to flow in the coil 45 which maintains the electromagnet 50 in its uppermost position with the plunger 51 and link 52 in the position shown in Figure 1. The plunger 51 and the mechanism 65 are at this time also in the position shown in Figure 1, the lever 67 being maintained in the position shown by reason of the flexible shaft 80 preventing the coil spring 69 from rotating the lever 67 in a clockwise direction.

Now should the thermostat 112 close indicating the need for heat in the spaces or regions being served by the unit heater 6, an electrical circuit will be completed through the electromagnet pilot valve unit 87, through the wires 110, 111, and 115. Upon energization of the latter unit, the solenoid armature 101 will be reciprocated vertically and the pilot valve member 91 will be caused to seat upon its upper seat closing the passageway through the plug 92. Communication of gas from port 90 through plug 92 will now be cut off and gas pressure within housing 35 and above diaphragm 38 will be released through port 95 to valve chamber 94 through the lower pilot valve into outlet chamber 97 and thence through the tube 98 to the auxiliary pilot burner 99. Upon release of pressure from above the diaphragm 38, the valve 32 will open with a snap action in the conventional manner of diaphragm type valves and gas will be permitted to flow through the pressure regulator and through the valve 32 and to the burner 5 for heating at the unit heater 6. Heat will be supplied as long as the thermostat 112 is closed and any suitable means may, if desired, be employed to control a fan or the like for forcing the air of the rooms or spaces being heated through the conduit 8 and cells 7 of the unit heater 6. With this type of unit heater, there is a very rapid exchange of heat between the gases of combustion within the heater and the air passing through the cells 7, that is, the air circulating through the cells rapidly carries away the heat of combustion of gases supplied through the conduit 4. If for any reason the device which forces the air circulation through the cells 7 should fail so as to cause the air to become stagnant, the amount of heat carried away by the air will be lessened to such an extent that the temperature within the unit heater and adjacent cells 7 will quickly rise to a relatively high and unsafe value at which danger exists of the cells 7 becoming burned.

For this reason, we employ the fusible link 81 mounted adjacent the cells 7 and in the event of the above described failure of air circulation the temperature adjacent the fusible link 81 rises to a relatively high value. This link will fuse thereby releasing the flexible shaft 80 and permitting the coil spring 69 to quickly rotate the lever 67 and its integral lug 77 in a clockwise direction. As described in the structural description, the lug 77 will engage the horizontal portion 75 of the lever 14 which in turn engages the nut 61 at the upper end of plunger 51 thereby forcing plunger 51 downwardly so that the center portion 11 of link 52 engages with the bolt 42 in a manner to instantly close the valve 32. Thus it will be seen that at a predetermined relatively high and unsafe value of temperature within the unit heater 6, the fusible link 81 fuses and causes immediate shut-down of the valve mechanism cutting off the supply of fuel to the burner. The fusible link arrangement provides a safety mechanism which assures elimination of the danger of the temperature within the unit heater becoming high enough to cause damage thereto.

If at any time, the flame of the pilot burner 11 which normally should burn constantly becomes extinguished thereby creating an unsafe condition in the unit heater, the thermo-couple 47 will be deenergized and likewise the flow of energizing current in the coil winding 45 will be discontinued and the coil spring 56 will instantly force the plunger 51 and the left end of link 52 downwardly in a manner to close the valve 32 in the same manner as has been described in connection with the closing of valve 32 by downward movement of the plunger 51. If the valve 32 is closed in this manner, fuel cannot again be supplied to the burner 5 until the electromagnetic device has been manually reset and the device will not remain in its reset position unless the flame of pilot burner 11 is again burning satisfactorily. Thus upon pilot flame failure, even if the thermostat 112 then calls for heat, the valve 32 will not be opened. Now if an operative manually relights the pilot burner 11, he may attempt to manually reset the electromagnetic device in the following manner. By moving the manual stem 76, as seen on Figures 1 and 2 and previously described, the lever 14 may be rotated in a clockwise direction causing the horizontal lug portion 75 to engage with the nut 61 causing the plunger 51 to be moved downwardly. As will be remembered, part 11 of link 52 is now engaged upon the bolt 42 and when plunger 51 is now moved downwardly the link 52 is rotated with the part 11 fulcrumed upon the head of the bolt 42. By thus forcing the plunger 51 downwardly, the plunger 51 is moved upwardly against the force of coil spring 56 and the electromagnet 50 may be returned to its previous position within the coil winding 45. During the manipulation just described, it will be understood that the downward force applied to plunger 51 and the reaction of coil 56 are both brought to bear upon the bolt 42 by part 11 of link 52 and therefore the valve 32 is kept firmly closed. Now if the pilot burner 11 has not been properly relit or if it has gone out after the operative has relit it, the electromagnet 50 will not stay in its upper position due to the thermo-couple 47 not being energized. Consequently, upon the operative releasing the manual stem 76, the plunger 51 will again move downwardly.

thus maintaining the valve 32 closed in the manner already described.

From the above, it is apparent that no gas whatever may be permitted to pass through the valve 32 after pilot flame failure, nor may any gas pass through valve 32 while an operative attempts to manually reset the mechanism for continued operation. The safety characteristics inherent in the apparatus are therefore obvious, and it will be appreciated by those skilled in the art that our apparatus provides positive insurance against the operative permitting a shot of gas to be admitted to the unit heater before he attempts to manually relight the pilot burner 11 by exposing a match or the like thereto.

Referring now to Figure 3 of the drawings, we have shown in this figure a slightly modified form of our invention in which we employ an ordinary pilot valve rather than a three-way pilot valve as we have disclosed in Figure 1. Those parts of the structure of Figure 3 which are identical with and correspond to similar parts of Figure 1 are numbered the same and those parts of the structure of Figure 3 which are modified are indicated by numerals greater than 200. It will be understood that the device of Figure 3 may be incorporated in the same system or a system similar to that of Figure 1 utilizing the same control devices. It will be seen that in Figure 3 the lower part of the plunger 257 forms a valve indicated at 202 which cooperates with a seat 203 formed by an opening through which the plunger 257 passes. The valve 202 forms an auxiliary valve and gas may be admitted therethrough to the interior of the housing 35 in a manner which we will presently explain. Within the body 1 of the valve is a port 204 which communicates with the inlet chamber 31 of valve 32 and which extends through the diaphragm 38, as shown, through part of the housing 35 and to the opening through which the plunger 257 extends. An adjustable needle valve 205 is disposed in a part of the port 204 extending through housing 35 and access may be had to this needle valve by means of a screw plug 206 engaging with housing 35, as shown. It will be seen that the lever 252 of Figure 3 has an upper part 211 corresponding to its similar part 11 as shown in Figure 1. With the parts in their normal position as seen in Figure 3, part 211 of the link 252 engages with the interior of the housing 35 as shown on the drawing so that the valve 202 is normally maintained in spaced relation from its seat so that gas may pass therethrough. If the plunger 51 is moved downwardly in the same manner as described in connection with Figure 1 to close valve 32, part 211 of the link 252 will disengage from the interior of housing 35 thereby permitting spring 62 to move plunger 257 upward slightly and thus immediately close the valve 202 as well as the valve 32.

The electromagnetic pilot valve unit 287 of Figure 3 is secured to the plate 237 in the same manner as that of Figure 1 having a similar gasket 289 disposed between the flange of the valve body and the plate portion 237. Number 295 indicates a port which extends through a part of the housing 35 through the plate portion 237, through the gasket 289 and through the valve body 288 so as to communicate with the pilot valve chamber 294. The pilot valve member 291 cooperates with a seat 293 and may open or close off communication to an outlet pilot valve chamber 297. The outlet valve chamber 297 commu-

nicates by a port 207 with a tube 298 corresponding to the tube 98 of Figure 1 which may lead to an auxiliary pilot burner similar to the auxiliary pilot burner 99 of Figure 1.

5 Referring to the operation of the modification of Figure 3, with the parts in the position shown the pilot valve member 291 is seated and the valve 202 is open. Thus gas may be communicated from the chamber 31 through the port 204 and the valve 202 to the interior of the housing 35 above the diaphragm 38 to maintain the valve 32 closed. Now in the event that valve member 291 should be lifted off of its seat in response to a call for heat by a thermostat or the like, gas 10 pressure will be released from above the diaphragm 38 through the port 295 past the valve seat 293 and through port 207 and tube 298 to the auxiliary pilot burner. Upon release of pressure from above the diaphragm 38, the valve 32 will open with a snap action in the customary manner of diaphragm type valves and gas will be supplied to the burner or the like for heating purposes. Whenever the thermostat becomes 15 satisfied, valve member 291 is seated and assumes the position shown in the drawings so that release of gas pressure from above the diaphragm 38 is terminated causing the valve 32 to be closed. As above described, in the event of pilot flame 20 failure the valve 32 may be closed in the same manner as described in connection with the modification of Figure 1, while at the same time the valve 202 is seated by reason of part 211 of link 252 no longer engaging the interior of the housing 35.

25 30 35 The electromagnetic thermo-couple responsive device may be reset by reciprocating the plunger 257 downwardly in the same manner as described in connection with Figure 1. If desired, the mechanism corresponding to the mechanism 65 of Figure 1 already described may also be used with the device of Figure 3. It will be seen that in Figure 3, we may employ an ordinary pilot valve rather than one of the three-way type and still in the event of pilot flame failure valve 202 40 will close thereby cutting off any bleed of gas which would permit unburned gases to accumulate in the unit heater.

45 50 55 While we have disclosed two modifications of our invention and pointed out the useful novelty, utility, and advantages thereof, we are aware that various modifications, variations, and changes may be made therein by those skilled in the art without departing from the spirit and scope of the invention. The disclosed embodiments are therefore to be interpreted as illustrative and the scope of our invention is to be limited only as determined by the appended claims.

60 We claim as our invention:

65 1. In a gas fired heating system including a main burner and a pilot burner, a control valve, valve closing means comprising an electromagnetic device normally energized by a thermo-couple responsive to the pilot flame, said means being arranged to release upon pilot flame failure for closing the valve, manual means cooperating with the valve closing means for repositioning the electromagnetic device to its energized position, means for operating said manual means for closing the valve when it is not closed by said electromagnetic device, and a fusible link normally restraining said operating means but releasing the same for operation upon the attainment of a predetermined high temperature.

70 75 80 85 90 95 2. In a control valve assembly, in combination,

a main valve, means forming a pressure chamber for controlling the main valve, an auxiliary valve for controlling the pressure in said chamber, temperature responsive mechanism operable at a predetermined temperature to close both said main valve and said auxiliary valve, said mechanism being constructed and arranged to act directly on said main valve and manual means cooperating with said mechanism and operable exteriorly of said valve assembly for maintaining said main valve closed, said manual means comprising a plunger formed by an extension of the stem of said auxiliary valve.

3. In a control valve assembly, in combination, a fluid flow control valve, an auxiliary valve associated with said control valve, resilient means urging said auxiliary valve in closing direction, temperature responsive means comprising a movable member for closing both valves, said means normally holding said auxiliary valve open and at a predetermined temperature moving said movable member in a direction to close said control valve and to cease holding said auxiliary valve open, said auxiliary valve having a reciprocable stem by reciprocation of which said movable member can be moved as a lever fulcrumed upon said control valve for closing said control valve.

4. In a control valve assembly comprising a valve body, in combination, a diaphragm type flow control valve, a member disposed above the diaphragm, means energizable in response to temperature attached to said member for normally maintaining it in spaced relation to the diaphragm, an auxiliary valve communicating with the space above the diaphragm, said auxiliary valve having a stem forming a plunger extending exteriorly of the valve body, resilient means associated with said plunger urging the auxiliary valve in closing direction, said member cooperating with said auxiliary valve normally keeping it open, said member being operable upon deenergization of said temperature responsive means to close the flow control valve and auxiliary valve, and said plunger being reciprocable to move said member in a manner to close the flow control valve.

5. In a control valve assembly, in combination, a diaphragm type flow control valve, a link member disposed above the diaphragm normally in spaced relation thereto for closing the valve, means forming a fulcrum above said link member, means pivotally attached to each end of said link, said means at one end of the link comprising a plunger extending exteriorly of the valve, an auxiliary valve communicating with the space above the diaphragm valve, the head of said auxiliary valve being formed by said plunger, resilient means urging said auxiliary valve in closing direction, said link normally engaging said fulcrum whereby said auxiliary valve is held open, said means at the other end of the link being actuatable in response to temperature to move the link out of engagement with said fulcrum for closing the auxiliary valve and to move the link into engagement with the diaphragm for closing the diaphragm valve.

6. In a control valve assembly, in combination, a main valve, a pressure motor comprising a variable pressure chamber and a movable wall connected to said valve, a pilot valve for controlling the pressure in said pressure chamber, means responsive to a first condition controlling said pilot valve thereby to position said main valve in accordance with the value of said first

condition, and means responsive to a second condition operative upon said second condition assuming a predetermined value to close said valve abruptly independently of the pressure in said chamber and accordingly independently of said first condition.

5 7. In a control valve assembly in combination, a diaphragm type valve, a pilot valve for normally controlling the diaphragm valve, normally inactive means responsive to temperature operable to bear upon said diaphragm valve for closing it, said last means comprising a thermocouple and an electromagnetic device energizable thereby.

10 8. In a control system, in combination, a main burner, a pilot burner, a diaphragm type valve controlling fuel flow to said main burner, a pilot valve normally controlling said main valve, temperature responsive means adapted to bear against said diaphragm valve for closing it at a predetermined temperature, said means comprising a thermo-couple responsive to the pilot flame and an electromagnetic device energizable thereby, and additional means responsive to heat from said main burner for actuating said first mentioned temperature responsive means for closing the diaphragm valve at a predetermined temperature.

15 9. In a control valve assembly, in combination, a main valve, means forming a pressure chamber for controlling the main valve, a pilot valve for controlling the pressure in said chamber and hence the position of said main valve, and means responsive to a controlling condition automatically operable at a predetermined value of said condition to close mechanically both said main valve and said pilot valve independently of the pressure in said chamber whereby flow through both valves is cut off.

30 10. In a control valve assembly, in combination, a diaphragm type valve, a pilot valve for normally controlling the pressure affecting the diaphragm valve and hence the position thereof, means responsive to a normal controlling condition for automatically positioning said pilot valve, means adapted mechanically and abruptly to move said diaphragm valve to closed position independently of the pressure affecting said valve, releasable means for normally retaining said previously named means in an inactive position, and means responsive to a second condition operative upon said condition assuming a predetermined undesired value to release said releasable means.

35 11. In combination, a main fluid fuel burner, a pilot burner therefor, main valve means controlling the flow of fuel to said main burner, a valve housing for said valve means having a main passage leading to said burner and an auxiliary passage, an electromagnet, an armature movable into engagement with said electromagnet, means responsive to the presence of a pilot flame for energizing said electromagnet sufficiently to hold said armature in engagement therewith but insufficiently to move it into engagement therewith, means associated with said armature for moving said valve means to a fuel flow preventing position when said armature is released from said electromagnet, resetting means for moving said armature into reengagement with said electromagnet, an auxiliary valve carried by and movable with said resetting means, and means including said main valve means and said auxiliary valve operable upon actuation of said resetting means to establish communication

between the inlet side of said valve means and said auxiliary passage while preventing the flow of fuel through said main passage to said main burner.

12. In combination, a main fluid fuel burner, a pilot burner therefor, main valve means controlling the flow of fuel to said main burner, a valve housing for said valve means having a main passage leading to said burner and an auxiliary passage, an electromagnet, an armature movable into engagement with said electromagnet, a thermocouple having its hot junction in the pilot flame for energizing said electromagnet sufficiently to hold said armature in engagement therewith but insufficiently to move it into engagement therewith, means associated with said armature for mechanically moving said valve means to a fuel flow preventing position when said armature is released from said electromagnet, resetting means for moving said armature into reengagement with said electromagnet, an auxiliary valve carried by and movable with said resetting means, and means including said main valve means and said auxiliary valve operable upon actuation of said resetting means to establish communication between the inlet side of said valve means and said auxiliary passage while preventing the flow of fuel through said main passage to said main burner.

13. In a control system, in combination, a main valve, a pressure motor comprising a variable pressure chamber and a movable wall connected to said valve, pilot valve means normally controlling the operation of said main valve by

controlling the pressure in said chamber, means responsive to a first condition controlling said pilot valve means to thereby position said main valve in accordance with the value of said first condition, and means responsive to a second condition for mechanically engaging and closing said main valve, independently of the pressure in said variable pressure chamber, whenever said second condition attains a predetermined value.

14. In a control system, in combination, a main valve, a pressure motor comprising a variable pressure chamber and a movable wall connected to said valve, pilot valve means normally controlling the operation of said main valve by controlling the pressure in said chamber, means responsive to a first condition controlling said pilot valve means to thereby position said main valve in accordance with the value of said first condition, a movable member in said variable pressure chamber, means biasing said member in a direction to mechanically close the main valve independently of the pressure in said chamber, a second condition responsive means normally retaining said member against its bias but adapted to release the same when said second condition attains a predetermined value, and means for manually resetting said movable member to its original position, said manual reset means including means mechanically holding said main valve closed during the resetting operation independently of the pressure in said chamber.
